UNITED STATES PATENT OFFICE.

MORRIS A. HEIMANN, OF ST. LOUIS, MISSOURI.

DESIGN FOR A SKIRT-HANGER.

SPECIFICATION forming part of Design No. 32,688, dated May 22, 1900.

Application filed April 23, 1900. Serial No. 14,053. Term of patent 7 years.

To all whom it may concern:

Be it known that I, MORRIS A. HEIMANN, of the city of St. Louis, in the State of Missouri, have invented a new and original Design for 5 a Skirt-Hanger, of which the following is a full, clear, and exact description, reference being had to the accompanying drawings, forming a part hereof.

The figure is a view in perspective showing 10 my complete design.

1 denotes upwardly-extending arms, each of which is formed from a single strand of wire twisted together in the manner shown. Each of the said arms is bent near its outer 15 end, forming a handle 2, the end of each of the arms projecting downwardly and outwardly, forming the supporting-hooks 3.

4 indicates the inner end of each of the

arms, which are wound together in the manner shown, forming the upwardly-projecting 20 handle, on the upper extremity of which is formed an integral hook 5. The upper portion of the said handle is formed by one end of each of the wires being twisted together, the opposite ends of the said wires being cut 25 away at 6.

I claim—

The design for a skirt-hanger, substantially as herein shown and described.

In testimony whereof I affix my signature 30 in presence of two witnesses.

MORRIS A. HEIMANN.

Witnesses:

ALFRED A. EICKS,
JOHN C. HIGDON.
